UNITED STATES PATENT OFFICE

ALWIN BORCHERS, OF DAYTON, OHIO, ASSIGNOR TO THE BROWN-BROCKMEYER COMPANY, OF DAYTON, OHIO, A CORPORATION OF OHIO

SHORT CIRCUITER FOR ELECTRIC MOTORS

Application filed July 24, 1931, Serial No. 552,920, and in Canada, July 18, 1931.

My invention relates to short circuiters for motor commutators.

My invention applies to a short circuiting device for alternating current motors of repulsion and induction type by which the motor is automatically changed from the repulsion starting condition to an induction running condition and vice versa, in accordance with variations of speed.

10 In particular, it is the object of my invention to provide a short circuiter in which there will be a plurality of contact segments held against outward movement and arranged to be supported so that when brought 18 into engagement with the commutator their yielding support will align them in engagement with the commutator and accommodate any variations in such engagement.

It is a further object to provide such segments so arranged that they may rock into engaging position but cannot move radially.

It is a further object to eliminate all spring means, such as garter springs and the like, for controlling the movement of these segments.

It is my object to provide fixed mechanism for restraining the movement of these segments, thereby eliminating spring mechanism heretofore employed which would permit their radial movement.

It is a further object to provide weight actuating means for moving the segments bodily. I thereby avoid using the segments as the weight means. It has heretofore been the custom and practice in this art to use centrifugal force on the segments to move them into engagement position. This leads to inaccuracy of contact and poor operation. These very heavy weights of my invention 40 will have no other function than to move the segments horizontally towards the commutator, while the weights will move radially.

It is my object to provide a single very strong spring to resist this movement in order to provide positive action for disengagement and engagement of the contact segments with the commutator.

To assist in this snap action I have provided means to resist the outward movement

of the weights and to suddenly relieve that resistance in order to insure snap movement.

Referring to the drawings, Figure 1 is a section through the commutator, segment support, spring, and centrifugal weights 55 showing the parts in position of rest out of contact.

Figure 2 is a similar view showing the parts in operation in contact.

Figure 3 is a section on the line 3—3 of 60 Figure 1.

Figure 4 is a section on the line 4—4 of Figure 1.

Figure 5 is a section on the line 5—5 of 65 Figure 1.

Figure 6 is a section on the line 6—6 of Figure 1.

Referring to the drawings in detail, 1 is an armature shaft upon which is mounted a 70 commutator 2 having commutator bars 3 insulated therefrom by the insulation 4. The face of these bars is cut away into an arcuate contact face as at 5. A plurality of contact making segments 6 are provided with an aligning slot 7, in which slot is inserted a 75 flat plate of yielding material 8. This disc of yielding material serves to align the contact segments and to yieldingly support them against the commutator when the segments are in commutator engaging position and to 80 thus accommodate any irregularities in contact with the commutator between the respective segments. The segments are prevented from having any outward movement by the overhanging lip 9 of the retaining disk 10. Both the disk 10 and the spring supporting disk 8 are mounted upon the insulating collar 11 on which they are held by the insulating clamping ring 12. This collar 85 is mounted upon a cam sleeve 13 having the cam flange 14 which is engaged by the foot 15 of the weights 16. This foot 15 has an engaging face 17 engaging the under side of the cam disk 14. The cam sleeve is mounted upon a bearing sleeve 18 on the armature shaft 1. The spring 19 engages the clamping ring 12 at one end and the armature 2 at the other end and resists the longitudinal movement of the bearing sleeve 18, cam sleeve 90

95

95

100

13, insulation sleeve 11, the yielding supporting disk 8 and the retaining disk 10.

This spring is compressed by the action of the weights 16 moving outwardly under centrifugal force against the cam sleeve flange 14. This movement is resisted by the ball bearings 20 carried in the foot 18 of each weight engaging with the shoulder 21 on the weight guide plate 22. This serves as a temporary resisting element to restrain the weights against centrifugal force so that they will suddenly move over this obstruction upon accomplishment of a predetermined speed of the armature shaft and thereby quickly make the engagement between the segments 6 and the commutator face 5.

This weight guiding plate is a cup shaped member mounted upon the collar 23 that is retained upon the armature shaft 1 and turns with it. The plate is provided with pairs of slots 24 through which the arms 25 of the weights 16 project to carry the weight feet 19 that are provided with the cam surfaces 17.

The weights 16 are arcuate members substantially constituting a full circle in their total length thereby making it possible to get a large amount of weight within a small space with constant, very positive action in making and breaking the contacts.

By this arrangement I am enabled to employ very heavy weights, to eliminate the usual quarter springs on the contact segments, to eliminate using contact segments as a centrifugal operating and circuit closing means and to employ a single, easily adjusted, powdered spring instead of a multiplicity of springs.

I am further enabled to assemble my weight guiding plate and weights in one assembly, the contact making segments and their supporting disk and retaining disk in another single assembly, and to mount or demount them as independent units. This facilitates manufacture, adjustment and repair. I insure perfect alignment of the contact segments by preventing any outward movement of the units, due to the overhanging lip 9 of the retaining disk 10. I provide for independent movement of the contact segments by permitting them to rock upon the spring plate 8 due to the slot 7. This permits them to align themselves upon the spring plate 8 and the spring plate 8 will yieldingly adjust them into engagement without any irregularities on the face 5 of the commutator 3.

I desire to comprehend within my invention such modifications as may be clearly embraced within the claim and scope of my invention.

Having thus fully described my invention, what I claim as new and desire to secure by Letters Patent, is:

1. In a short circuiting mechanism, an armature shaft, an armature, a reciprocal

support on said armature shaft, a plurality of contact making segments mounted thereon, yielding means for supporting and aligning said segments, said segments being arranged around the yielding means, and weight means adapted to move said segments into contact making position and yielding means to resist the movement of said weight means.

2. In a short circuiting mechanism, an armature shaft, an armature, a reciprocal support on said armature shaft, a plurality of contact making segments mounted thereon, yielding means for supporting and aligning said segments, and weight means adapted to move said segments into contact making position and yielding means to resist the movement of said weight means, and means engaging said contact making segments adapted to prevent their outward movement.

3. In a short circuiting mechanism, an armature shaft, an armature, a reciprocal support on said armature shaft, a plurality of contact making segments mounted thereon, yielding means for supporting and aligning said segments, weight means adapted to move said segments into contact making position and yielding means to resist the movement of said weight means, and means engaging said contact making segments adapted to prevent their outward movement, said segments being arranged with aligning slots therein in which said yielding support therefor is mounted whereby said segments have limited rocking movement on said yielding support.

4. In a short circuiter, an armature, an armature shaft, a plurality of contact segments, a spring plate supporting said segments, and means for moving said segments into and out of engagement with said commutator.

5. In a short circuiter, an armature, an armature shaft, a plurality of contact segments, a spring plate supporting said segments, and means for moving said segments into and out of engagement with said commutator, said segments having an aligning slot for receiving said spring plate, said slot being of sufficient width to permit limited rocking of said segments independently one of the other on said spring plate.

6. In a short circuiter, an armature, an armature shaft, a plurality of contact segments, a spring plate supporting said segments, and means for moving said segments into and out of engagement with said commutator, said segments having an aligning slot for receiving said spring plate, said slot being of sufficient width to permit limited rocking of said segments independently one of the other on said spring plate, and means encircling said segments partially adapted to engage their outer surfaces to prevent outward movement of said segments on said spring plate.

7. In combination, an armature shaft and commutator, a plurality of slotted circular segments, a spring plate slidably mounted on said armature shaft inserted in said slots, 5 weight means adapted upon predetermined speed of the armature shaft to move said segments into engagement with said commutator and spring means adapted to return said segments to their initial position upon the 10 reduction of the armature shaft to a predetermined speed.

8. In combination, an armature shaft, an armature and a commutator having an arcuate engaging face, a slidable spring plate 15 mounted on said armature shaft, a plurality of independent contact making segments having arcuate engaging faces mounted on the periphery of said spring plate, a retaining ring associated with said spring plate 20 engaging the outer surfaces of said segments and retaining them on said spring plate, weight means for moving said spring plate segments and retaining means towards the commutator, and spring means between said 25 spring plate and armature for resisting said movement, said spring plate and retaining means being insulated from said armature shaft and spring.

9. In combination, a commutator, an armature shaft, a cam sleeve and cam flange, an insulation sleeve, a yielding supporting disk, a plurality of segments mounted thereon, a retaining disk having a retaining lip engaging said segments to retain them between it and said supporting disk, a plurality of weights having cam faces engaging said cam sleeve flange and means for guiding said weights against said flange to move said contact making segments against said commutator and yielding means for resisting said movement.

10. In combination, a commutator, an armature shaft, a cam sleeve and cam flange, an insulation sleeve, a yielding supporting disk, a plurality of segments mounted thereon, a retaining disk having a retaining lip engaging said segments to retain them between it and said supporting disk, a plurality of weights having cam faces engaging said cam sleeve flange and means for guiding said weights against said flange to move said contact making segments against said commutator and yielding means for resisting said movement, and means for temporarily 55 resisting the movement of said weights.

11. In combination, a commutator, an armature shaft, a cam sleeve and cam flange, an insulation sleeve, a yielding supporting disk, a plurality of segments mounted thereon, a retaining disk having a retaining lip engaging said segments to retain them between it and said supporting disk, a plurality of weights having cam faces engaging said cam sleeve flange and means for guiding 60 said weights against said flange to move

said contact making segments against said commutator and yielding means for resisting said movement, and means for temporarily resisting the movement of said weights, and guiding means for said weights adapted to 70 guide them in a diagonal path towards said commutator.

12. In a short circuiter, an armature shaft, a commutator, having an arcuate face, a plurality of circular segments having aligning 75 slots, a yielding supporting disk mounted in said slots, a retaining disk engaging the outer margins of said segments, a supporting insulating sleeve, a spring engaging said sleeve located between the sleeve and the commutator and an angularly disposed cam sleeve supporting the insulating sleeve, a bearing sleeve therefor, a plurality of weights having cam faces engaging said cam sleeve, and means for guiding said weights towards said 80 cam sleeve.

13. In a short circuiter for repulsion and induction motors, centrifugal actuating weight means, yielding means for resisting said weight means, a plurality of rocking 85 contact making segments, yielding means for supporting said segments, and positive mechanical means for preventing outward movement of said segments.

14. In a short circuiting mechanism, an armature shaft, an armature, a commutator, a plurality of contact making segments supported on the armature shaft, yielding means for supporting and aligning said segments, said segments being arranged around the 95 yielding means, and independent weight means adapted to move said segments into contact making position and yielding means to resist the movement of said weight means.

15. In a short circuiting mechanism, an armature shaft, an armature, a commutator, a plurality of contact making segments supported on the armature shaft, yielding means for supporting and aligning said segments and independent weight means adapted to move said segments into contact making position and yielding means to resist the movement of said weight means, and means for positively limiting the outward movement of 100 said segments whereby said segments can only be moved laterally against the commutator by the action of said weights against the resistance of said yielding means.

In testimony whereof, I affix my signature.

ALWIN BORCHERS.
